ADJUSTABLE SUPPORT

Thomas A. McGregor, Pontiac, Mich., assignor to
 American Forging & Socket Company, Pontiac,
 Mich., a corporation of Michigan

Application May 31, 1938, Serial No. 210,856

3 Claims. (Cl. 155—14)

This invention relates to adjustable supporting means for the seats of vehicles, and other objects desired to be mounted in a manner rendering them easily movable at will, but normally held against unwanted movement with such rigidity as to prevent rattling, looseness, or side or end play.

An important object of the invention is to provide a device of the indicated character which is simple and inexpensive construction but great strength.

A further object is to incorporate in an adjustable support of such character an improved locking mechanism, easily releasable under all conditions yet normally holding the supported object rigidly against movement.

Still another object is to provide such an improved support which may be formed as a unitary track and carriage assembly, and to incorporate means whereby a plurality of such assemblies may be interconnected to provide for synchronizing movement of the carriage sections of such interconnected units. A related object is the provision of a device of the indicated character which is readily attachable and detachable with respect to the inter-connecting-synchronizing means.

In the drawings:

Figure 1 is a plan view of a pair of unitary supporting assemblies constructed in accordance with the principles of this invention, and arranged and interconnected to support a vehicle seat, the interconnecting means being centrally broken away.

Figure 2 is a side elevational view of one of the supporting units.

Figure 3 is a front elevational view of such unit.

Figures 4 and 5 are top and side views, respectively, of the locking lever.

Figures 6 and 7 are rim and end views, respectively, of one of the roller gear elements, and

Figure 8 is a view similar to Figure 3, showing a somewhat modified construction.

Referring now to the drawings, reference character 10 designates a channeled track, riveted or otherwise attached to a support 12 adapted to be fastened as by bolts 13 to a floor or other suitable surface. The track is also provided with laterally out-turned top flanges 14.

A carriage member 15, rollably supported by the track in inverted position, is of similar cross sectional contour and carries upwardly extending studs 17 by which a supported object such as the seat 20 may be attached thereto. Rollers 22 in-

terposed between the track and carriage fit snugly into the aligned channels of such members, each roller also having a toothed gear portion 24 meshing with appropriately positioned serially perforated openings as 25, 26 in the carriage and 5 track portions.

The form of the roller is clearly shown in Figures 6 and 7. Its two halves are clinched together to form a unit and to secure between them the stamped gear 24. The metal for clinching is pressed outwardly from the hub of one of the roller sections and adapted to project through a central opening in the other. The projected portion is also hollow and the opening 29 thus formed in the roller is elongated in form and 15 adapted to receive the flattened end of a torque rod 30, projectable thereinto through a slot 33 in the side of the inner guide element 35. Such slot is long enough to allow the rod to travel with the rollers as the carriage moves. The inner and 20 outer guide elements 35, 36, respectively, are attached to the carriage and provided with flanges adapted to underhang the track flanges 14, to prevent vertical separation of the carriage from the track.

It will be appreciated that the torque rod 30 provides means whereby a plurality of such units may be interconnected to synchronize movement of their carriage portions. In the illustrated assembly one complete track and carriage assembly 30 is arranged to support each end of the seat, and the torque rod insures uniform movement of both carriages even though the force to move the seat be applied entirely at one end. The cross connecting means provided by the torque 35 rod also eliminates the necessity of locking the carriage to the track at more than one of such assemblies.

The locking means comprises a lever 40, of channel section, pivotally connected to the inner 40 guide member 35 and projected outwardly through an appropriately positioned opening 41 in the outer guide member 36, of one of the assemblies. In vehicular installations, this is preferably on the driver's side. The cross-web of the 45 channel-shaped locking lever is terminated short of its pivoted end, to form perforated ears 42 at that end, which ears extend through slots (un-designated) in the inner guide channel 35. A cotter pin 44 is thereafter passed through the 50 perforations to prevent removal of the lever, which is then located by the cotter pin in co-operation with the web of the lever. Along the edge of one of the track flanges 14 a series of notches 46 are cut, and the spacing of these con- 55

forms to the distance between the downwardly projecting flanges of the locking lever. Such flanges of the lever are angularly cut away to provide downwardly projecting toothed portions 5 45 projectable into the slots when the lever is in the lowered position in which it is normally yieldably held by the spring 47. When the outer end of the lever is lifted, the toothed portions 45 are raised to free them from the slots, allowing the 10 carriage to travel over the track. The spring is of substantially straight wire, held between ears 48, 59 pressed out of the outer guide channel 36, and turned downwardly at its free end into a hole 43 in the locking lever.

15 In the somewhat modified construction shown in Figure 8 guide portions 35A, 36A, which are arranged and function similarly to guide portions 35, 36 of the embodiment just described, are formed as integral extensions of the flanges of 20 the carriage portion 15A. These flanges in similar fashion underhang and are freely slideable with relation to the head flanges of the track element 10A. The other portions of this embodiment 25 equivalent to parts previously described are believed to need no detailed redescription, and have been given like reference numerals distinguished by the addition of the letter "A" to each.

While it will be apparent that the illustrated embodiments of my invention herein disclosed are 30 well calculated to adequately fulfill the objects and advantages primarily stated, it is to be understood that the invention is susceptible to variation, modification and change within the spirit and scope of the subjoined claims.

35 What I claim is:

1. Adjustable supporting means comprising a track, a carriage assembly rollable thereover and having substantially parallel side flanges overhanging opposite sides of the track, a locking dog 40 member carried by said carriage assembly, extending transversely through both side flanges thereof, and movable to and from engagement with said track, and spaced downwardly extending holding portions carried by said dog member 45 and movable therewith into and out of interfitting relation with conformably spaced abutment portions formed upon and spaced longitudinally along the track, said track being of channeled form and having side webs projecting upwardly 50 toward said holding portions of the dog member and notched at intervals conforming to the spacing of said holding portions, said notches con-

stituting the abutment portions and being adapted to interlock in transverse relation with said holding portions.

2. Adjustable supporting means comprising a track, a carriage assembly rollable thereover and having substantially parallel side flanges overhanging opposite sides of the track, a locking dog member carried by said carriage assembly, extending transversely through both side flanges thereof, and movable to and from engagement with said track, and spaced downwardly extending holding portions carried by said dog member and movable therewith into and out of interfitting relation with conformably spaced abutment portions formed upon and spaced longitudinally 15 along the track, said dog member comprising a channel having downwardly extending side webs, said webs being elongated at one end and rockably projecting through individual slots in one flange of the carriage, said holding portions comprising portions of the side webs of said channel, and said abutment portions comprising a plurality of serially disposed cut out areas spaced correspondingly to the spacing between the side of the webs of said channeled dog member. 25

3. Adjustable supporting means comprising a track, a carriage assembly rollable thereover and having substantially parallel side flanges overhanging opposite sides of the track, a locking dog member carried by said carriage assembly, extending transversely through both side flanges thereof, and movable to and from engagement with said track, and spaced downwardly extending holding portions carried by said dog member and movable therewith into and out of interfitting 30 relation with conformably spaced abutment portions formed upon and spaced longitudinally along the track, said track and dog member comprising channels extending perpendicularly to one another and the side flanges of each member being directed toward those of the other member, the dog member being pivotally connected to one of the side webs of the carriage assembly and 35 slidably projecting through the other side web of said assembly, said holding portions comprising portions of the side webs of said channeled dog member and said abutment portions comprising a plurality of serially disposed cut out areas spaced correspondingly to the spacing between the side webs of said dog member. 40 45 50
